CASSEROLE OR SIMILAR ARTICLE

John P. Johnson, Montrose, N.Y., assignor to Textile Machine Works, Wyomissing, Pa., a corporation of Pennsylvania

Filed Feb. 23, 1961, Ser. No. 64,032

Term of patent 14 years

(Cl. D44—15)

Fig. 2

FIG. 1 is a top plan view of a casserole or similar article showing my new design, a repeat unit of the motif being shown within the dashed lines; and

FIG. 2 is an elevational view thereof, the motif on the side opposite being the same as that shown, and the motif on the cover being omitted for convenience of illustration.

The dominant features of my design reside in the portions shown in full lines.

I claim:

The ornamental design for a casserole or similar article, as shown and described.
